COMBINED HOT WATER BOILER AND
WASHING MACHINEStig Vilhelm Jakobsson, Goteborg, Sweden, assignor to
Kungspannan, S. Jakobsson, Goteborg, Sweden, a cor-
poration of Sweden

Filed Dec. 14, 1960, Ser. No. 75,843

6 Claims. (Cl. 68—16)

This invention relates to a washing machine placed within the water space of a hot water boiler.

In villas and other dwelling houses it is usual to arrange the heating boiler in one room, the boiler room, and the washing machine, the dryer and the like in another room, the laundry room.

The main feature of the present invention is to provide in a compartment of the water room of a boiler, separated from the main water room of the boiler, a washing machine having an outer shell. The compartment of the boiler may be defined by a partition containing passages. This invention gives rise to the following advantages:

(a) The washing water introduced into the washing machine is rapidly heated by the boiler water to a temperature which may be adjusted manually or by means of a thermostat.

(b) It is easy to obtain pre-heated air for drying the laundry.

(c) The heat economy of the combined hot water boiler and washing machine is very high.

The invention will now be described with reference to the accompanying drawing. In the drawing:

FIG. 1 is a vertical cross section through a heating boiler combined with a washing machine, and

FIG. 2 is a top view of a portion of a heating boiler containing a washing machine according to a modification of this invention.

The heating boiler shown in FIG. 1 is heated by means of an oil burner assembly 1 having its jet 2 extending downwards into a combustion chamber 3. The latter communicates with a fireplace 4 having a fire grate 5 on which wood, coke or other solid fuels may also be burned. The combustion gases are evacuated through the flue 6. The combustion chamber 3, the fireplace 4 and the flue 6 are all surrounded by a water boiler 7, which also surrounds heat exchanger coils 8 which have a feed pipe 9 for cold water and a discharge pipe 10 for water which has been heated in the boiler. A heat insulating layer 11 is arranged around the water boiler 7. The forementioned elements are protected by a removable or hinged cover 12.

At one end of the stand 13 of the boiler there is arranged a container 14 which comprises an extension or a compartment of the water boiler 7 separated from the latter by a partition 15 which contains passages 16 and 17 for the boiler water. A perforated washing cylinder 20, having a cover 19, is surrounded by an outer shell 18 which is immersed in the boiler water and extends down into the container 14. The washing cylinder 20 is driven by an electric motor 22 by a V-belt 21. The motor 22 is arranged in a chamber 23 below the container 14. 24 denotes a suitable transmission to drive the washing cylinder 20. The laundry loading and unloading opening 25 is provided with a cover 26, and the cover 26 is protected by a removable and insulated cover 27 which is situated level with the cover 12.

The washing machine is provided with a feed pipe 29 for cold water controlled by a tap 28, and the shell 18 is at the bottom provided with a drain tube 30 for the washing water.

A blower 31 is arranged in the chamber 23 and from said blower 31 there extends an air duct 32 which extends through the container 14 and has a corrugated wall. The

2

duct 32 ends in a downwards directed jet 33 on the inside of the shell 18. The air duct 32 is located in the container 14 which is filled with hot water from the boiler. The air passing through the duct from the fan 31 is thus heated by the boiler water.

The washing machine is preferably also provided with transmission 24 so that the washing cylinder can be driven with a high speed in such a way that it can serve also as a centrifuge for drying clothes.

One of the passages 16, 17, preferably the lower one 16, is provided with a control valve 34. The opening movements of said valve 34 are controlled by a thermostat 35 disposed in the container 14. The valve 34 is preferably also provided with a device for its manual adjustment.

The outer shell 18 is kept hot as boiler water continuously flows along the outer side of said shell 18.

When the washing machine is to be used and cold water is fed through the conduit 29, this water is rapidly heated by the hot shell 18. The washing machine can thus be used practically at once. The wash temperature is maintained by the control device which controls the valve 34 and it is also determined by the size of the passage 16. The boiler water streams through the passage 17 in the wall 15, delivers heat to the shell 18 and escapes then through the passage 16 to be reheated at its passage around the fire place 4 and the combustion chamber 3. After washing the laundry in the washing cylinder 20, the wash water is discharged through the tube 30. The washing cylinder 20 may then be driven as a centrifuge. In the last phase of the drying the blower 31 is started and forces air through the duct 32 in which it is heated and is finally forced through the jet 33 downwards along the inside of the shell 18 and through the laundry which is then dried to any desired degree. During the drying in the washing cylinder 20, now serving as a "drying tumbler," the covers 26 and 27 should be opened. Upon removing the laundry from the cylinder 20 it can be hung in the rather hot boiler room.

FIG. 2 illustrates the invention when used in connection with a washing machine having a vertical drive shaft 36. The arrangement of the air duct 32' is easily understood from this figure. An inlet tube 29' having a valve 28' debouches in the outer shell 18' of the washing machine. The tube 29' is connected to the cold water conduit 9' of the hot water boiler 8'. The drain tube for the washing water has been denoted 30'.

The present invention has been described in detail above for purposes of illustration only and is not intended to be limited by this description. Thus, the type of heating boiler and the type of washing machine is independent of the invention. The valve 34 controlled by the thermostat might be arranged in the passage 17 instead of in the passage 16. The blower 31 may be driven by the shaft 36 of the motor 22. The wall 15 can be heat insulated and it is possible to arrange valves in the passages 16 and 17 so as to cut off the flow of boiler water from the container 14.

What I claim is:

- 60 1. A combined dwelling house heating boiler and a washing machine comprising, in combination,
  - (a) a water space of said boiler,
  - (b) means heating the water space of said boiler,
  - (c) a shell of a washing machine disposed in the water space of said boiler, said shell having an opening leading outside said boiler,
  - (d) a rotatably mounted washing cylinder containing perforations, said washing cylinder being disposed within said shell,
  - (e) means to rotate said washing cylinder,
  - (f) a duct leading through said water space of said boiler into said shell, and

- (g) a blower to force air through said duct into said shell about said washing cylinder.
2. The combination according to claim 1 with the addition of heat radiating means projecting into said duct.
3. The combination according to claim 2 wherein said heat radiating means projecting into said duct comprises at least one corrugated wall of said duct.
4. In a combined dwelling house heating boiler and a washing machine,
- (a) a water space of said boiler,
  - (b) means heating the water space of said boiler,
  - (c) a partition forming a compartment within the water space of said boiler, said partition containing at least two passages disposed one above the other,
  - (d) a shell of a washing machine disposed in the water space of said boiler within said compartment, said shell having an opening leading outside said boiler through which laundry is loaded and unloaded from said washing machine,
  - (e) a perforated washing cylinder rotatably mounted 20 within said shell,

- (f) means to rotate said washing cylinder,
- (g) a duct leading through the water space of said boiler into said shell, and
- (h) a blower to force air through said duct into said shell about said washing cylinder.
5. The combination according to claim 4 with the addition of valve means at least partially closing one of said passages through said partition.

6. The combination according to claim 5 with the addition of thermostatic control means in said compartment at least partially closing said valve means.

- (f) means to rotate said washing cylinder,
- (g) a duct leading through the water space of said boiler into said shell, and
- (h) a blower to force air through said duct into said shell about said washing cylinder.

5. The combination according to claim 4 with the addition of valve means at least partially closing one of said passages through said partition.

6. The combination according to claim 5 with the addition of thermostatic control means in said compartment at least partially closing said valve means.
